Inv. Edward V. Burns

Charles W. Hill, Atty.

UNITED STATES PATENT OFFICE.

EDWARD V. BURNS, OF CHICAGO, ILLINOIS, ASSIGNOR TO WILSON-JONES LOOSE LEAF CO., OF CHICAGO, ILLINOIS, A CORPORATION OF ILLINOIS.

RING-BOOK MECHANISM.

1,188,037.

Specification of Letters Patent. Patented June 20, 1916.

Application filed July 2, 1914. Serial No. 848,553.

To all whom it may concern:

Be it known that I, EDWARD V. BURNS, a citizen of the United States, and a resident of the city of Chicago, in the county of Cook and State of Illinois, have invented 5 certain new and useful Improvements in Ring-Book Mechanism; and I do hereby declare that the following is a full, clear, and exact description of the same, reference 10 being had to the accompanying drawings, and to the numerals of reference marked thereon, which form a part of this specification.

This invention relates to an improved 15 form of ring book mechanism adapted for use in loose leaf books and the like, embracing a plurality of sets of interlocking ring sections, each set independently operable by means of suitable finger pieces or 20 levers for the purpose.

By my invention an improved arrangement 25 of the parts is secured whereby the assembly of the different elements is greatly facilitated and simplicity of manufacture assured.

It is an object of this invention to construct a mechanism wherein ring sections 30 are secured upon releasably connected toggle bars mounted on a resilient base plate with small leaf springs inserted between the edges 35 of the base plate and said toggle bars, and with a slotted cover plate fitted over said base plate to inclose the toggle bars and acting to hold finger actuating levers in position whereby said toggle bars may be actuated to open the rings.

It is furthermore an object of this invention to construct a ring book wherein toggle levers are resiliently mounted between a 40 base and cover plate which are resiliently engaged together and with ring sections mounted on said toggle bars, so that when said toggle bars are sprung upwardly from the base plate by suitable actuating levers 45 for the purpose, said ring sections open to permit the insertion or removal of pages.

It is finally an object of this invention to construct a device consisting of few parts 50 easily and cheaply manufactured, and so constructed and arranged that the assembly thereof is a simple operation.

The invention (in a preferred form) is illustrated in the drawings and hereinafter more fully described.

55 In the drawings: Figure 1 is a top plan

view of an open loose leaf book equipped with a mechanism embodying the principles of my invention. Fig. 2 is a top plan view of the mechanism with the cover plate thereof removed and one set of the links and toggle bars omitted. Fig. 3 is a fragmentary section with parts in elevation taken on line 3—3 of Fig. 1. Fig. 4 is a view partly broken away similar to Fig. 3, but with the parts shown in unlocked or release position. Fig. 5 is a detail section taken on line 5—5 of Fig. 2. Fig. 6 is a detail section taken on line 6—6 of Fig. 3. Fig. 7 is a detail section taken on line 7—7 of Fig. 2.

As shown in the drawings: My device is 70 associated with a loose leaf book, the covers of which are denoted by the reference numeral 1, with the pages 2, retained therein by means of a device embodying the principles of my invention. The ring retaining 75 mechanism for the pages embraces a curved resilient base plate 3, the outer convex side of which lies against and is secured to the covers 1, of the book, and the margins of said resilient plate are flanged inwardly toward one another, as denoted by the reference numeral 4. Engaged within the flanged portion 4, of said resilient base plate are wave-like leaf springs 5, two being provided on each side of the plate, and each extending half the length thereof. Two sets of ring carrying toggle bars, each extending half the length of the base plate, are mounted therein, the edges of the toggle bars or plates fitting into the flanged margins of 80 said base plate, and bearing against the leaf springs therein. Each of the respective toggle bars are provided with offset tongues 7, which form a hinged connection therebetween and yet do not positively connect the 85 same together. Rigidly secured upon said toggle plates 6; by brazing or otherwise, are interfitting substantially semi-circular ring sections 8, and, when the toggle plates are sprung upwardly, as shown in Fig. 5, in 90 dotted lines, and in full lines in Fig. 4, the ring sections are opened away from one another. For the purpose of springing said toggle plates upwardly to open the rings a finger piece or rocking lever 9, is provided 95 having tongues 10, extending laterally from each side thereof to lie in slots cut in the flanged portions 4, and also bearing against the ends of the plates 6, of the resilient base plate, permitting said levers, one being pro- 100 105 110

vided at each end of the device, to rock about the tongues as a pivot point. However, in order to relieve the small tongues 10, of the stress exerted upon the mechanism when the finger piece is depressed to elevate the toggle plates, said finger pieces are each provided with a downstruck rounded portion 11, which is curved and normally rests upon the bottom of the base plate, so that the effort exerted against the toggle plate in springing the same upwardly is transmitted through the actuating lever to the base of the resilient plate and not through the tongues 10.

15 In order to conceal the operating mechanisms and assist in retaining said finger pieces 9 in position a cover plate 12 is flanged at its margins to fit over and around the flanged portions 4, of the base plate 3, and is slotted to permit free movement of the ring sections 8, which extend through said slots.

The operation is as follows: As already pointed out in the description there are two sets of ring sections, each operable independently of the other, a finger piece 9, being provided at each end of the mechanism, one for each of said sets of rings, so that in opening the rings for the insertion or removal of a page, one set of rings may be first opened and the proper operations proceeded with, then the rings closed and the other sets of rings opened. This is particularly advantageous in books at times when the same are filled practically to their full capacity with pages, for the reason that where all of the rings are opened simultaneously, often times a number of the pages spring upwardly and are disengaged, thus inconveniencing the user of the book. It is a notable feature of the present invention that bolts, screws, or other attaching means are entirely omitted, all of the parts being rigidly associated with one another, due to the resiliency of certain 45 of the members.

In assembling the device the toggle plates 6, with the rings thereon are first fitted between the inturned flanges 4, of the resilient base plate 3, and then by springing the base plate outwardly a slight amount sufficient space is afforded between the edges of the loosely fitting toggle plates and the inner walls of the inturned portions 4, of the base plate to permit the ready insertion of the leaf springs 5, the respective pairs thereof, there being four in all, being inserted at opposite ends of the base plate. The actuating levers or finger pieces 9, are next inserted with the tongues 10, thereof lying in the cut away or slotted portions of the flange members 4, of the base plate, and finally the cover plate 12, is sprung over the folded portions 4, of the base plate, thus concealing the mechanisms therein and assisting by 65 means of indent portions in holding the

tongues 10 in their respective slots in operating position.

It is apparent that wide variations may be made in the various details of construction, but I do not purpose limiting the patent 70 granted otherwise than necessitated by the prior art.

I claim as my invention:

1. In a ring book mechanism a flanged base plate, toggle plates releasably engaged 75 between the margins thereof, sectional rings secured on said toggle plates, actuating means pivoted at the margins of said base plate and engaging beneath said toggle plates to spring the same upwardly to open the ring sections and a flanged cover plate adapted to resiliently fit over and around the flanges of said base plate to conceal the operating mechanisms and retain the actuating means in position. 80

2. In a device of the class described a resilient base plate having inwardly folded margins, toggle plates hingedly connected and releasably mounted with their edges engaging in said folded margins of the base plate, ring sections secured on said toggle plates, pivoted means for springing said toggle plates upwardly to open the ring sections, a plurality of rockers integral with said means bearing on said base plate to relieve the pivots of strain when said means are actuated, and a cover plate resiliently engaged over said base plate to inclose the mechanisms therein and slotted to permit projection and movement of the ring sections 95 therethrough. 100

3. In a device of the class described a resilient base plate, toggle plates hingedly connected and mounted therein, means for springing said toggle plates upwardly comprising a finger piece having integral tongues engaged in the slotted portion of said base plate, said finger piece constructed to rest on the bottom of said base plate when springing the toggle plates upwardly to relieve the pivot tongues of stress, and a cover plate engaging over the base plate concealing the toggle plates therein and holding said actuating finger pieces engaged in position in the base plate. 110

4. In a device of the class described a base plate, toggle plates mounted therein, actuating means for swinging said toggle plates upwardly pivoted at the margins of said base plate and detachable therefrom, and a cover plate resiliently engaged over the upper portion of the base plate and inclosing said toggle plates therewithin. 115

5. In a device of the class described a resilient supporting member, hingedly connected means releasably mounted therein, ring sections mounted on said means, pivoted mechanism for operating said means to open said ring sections, bearing members integral with said mechanism resting on said 120 125

supporting member adapted to relieve the pivoted parts of stress when said mechanism is operated, and a cover plate secured over said supporting member to inclose the mechanisms therewithin.

6. In a ring book mechanism a resilient base plate, resilient means in the margins thereof, toggle plates releasably connected with said base plate bearing against said means, sectional rings secured on said toggle plates, and actuating means pivoted at the margins and also bearing upon the inner surface of said base plate adapted to simultaneously swing said toggle plates and said 15 rings upwardly and outwardly respectively.

7. In a device of the class described a base plate, a plurality of springs in each margin thereof, toggle plates mounted within said base plate and bearing at their edges upon 20 said springs, actuating means for swinging said toggle plates upwardly pivoted in recesses in the margins of said base plate and detachable therefrom, and a resilient cover plate fitting over said base plate and inclosing said toggle plates therewithin.

8. In a device of the class described a resilient base plate, a plurality of sets of hingedly connected toggle plates releasably engaged between the margins thereof, 25 sectional rings secured on said toggle plates, and actuating means pivoted at the margins of said base plate and engaging beneath said toggle plates to spring the same upwardly to open the ring sections.

30 9. In a device of the class described a base plate, a plurality of sets of toggle plates connected thereto, rings secured on said toggle plates, pivoted actuating means for independently operating each set of said 35 toggle plates, and a cover secured over said base plate to inclose the toggle plates therewithin.

40 10. In a device of the class described the combination with a resilient base member, of a plurality of spring means in each margin thereof, a plurality of pairs of rocking mechanisms engaged between the margins of 45 said base member, a plurality of sectional rings mounted on said rocking mechanisms, and a plurality of pivotal actuating means for opening said rings by actuating said mechanisms.

of said base member, a plurality of sectional rings mounted on said rocking mechanisms, a plurality of pivoted actuating means for 50 opening said rings by actuating said mechanisms, and a resilient cover for inclosing and retaining the various parts in place.

11. In a device of the class described the combination with a base plate, of a plurality 55 of sets of ringed intermeshing toggle plates thereon, and pivoted actuating means for said toggle plates.

12. In a device of the class described the combination of a base plate, a cover plate 60 thereon, a plurality of ringed toggle plates therebetween, springs between said base plate, and said cover plate, and pivotal actuating means for said toggle plates, comprising pivoted tongues, and rocker members 65 adapted to continuously rest on said base plate, said rocker members adapted to relieve said tongues of stress exerted on said actuating means when depressed to elevate the toggle plates.

70 13. In a device of the class described a base plate, a plurality of sets of toggle plates connected thereto, rings secured on said toggle plates, and pivoted actuating means for independently operating each of said 75 sets of toggle plates.

14. In a device of the class described the combination with a resilient base member, of a plurality of spring means in each margin thereof, a plurality of pairs of rocking 80 mechanisms engaged between the margins of said base member, a plurality of sectional rings mounted on said rocking mechanisms, and a plurality of pivotal actuating means for opening said rings by actuating said 85 mechanisms.

In testimony whereof I have hereunto subscribed my name in the presence of two subscribing witnesses.

EDWARD V. BURNS.
